UNITED STATES PATENT OFFICE.

WILLIAM J. MURPHY, OF CEDAR FALLS, IOWA.

DESIGN FOR A TIRE-TREAD.

59,125.

Specification for Design. Patented Sept. 20, 1921.

Application filed April 4, 1921. Serial No. 458,547. Term of patent 14 years.

To all whom it may concern:

Be it known that I, WILLIAM J. MURPHY, a citizen of the United States of America, and a resident of Cedar Falls, Blackhawk county, Iowa, have invented a new, original, and ornamental Design for Tire-Treads, of which the following is a specification, reference being had to the accompanying drawing, forming part thereof.

Referring to the illustrations, Figure 1 is a

fragmentary plan of an elastic vehicle tire embodying my ornamental design; and

Fig. 2 is a transverse section thereof taken on the line 2—2 of Fig. 1.

I claim:

The ornamental design for a tire tread as shown.

Signed at Waterloo, Iowa, this 19th day of March, 1921.

WILLIAM J. MURPHY.
